UNITED STATES PATENT OFFICE

WILLIAM P. LOWTHER, OF MERCED, CALIFORNIA

TANK FILLER-CAP LOCK

Application filed July 5, 1932. Serial No. 620,783.

This invention relates to tank filler-cap and lock units and particularly represents improvements over the structure shown in my Patent No. 1,867,919, dated July 19, 1932.

5 In the construction of the previous lock the turning movement of the key to an unlocking position caused the locking tongues to be initially raised in the filler tube or barrel from which with the rough tubes or pipes 10 usually used for the purpose tended to cause the tongues to stick and prevented the easy release of the same.

The principal object of the present invention is to retain all the advantages of the 15 previous structure while mounting the swinging arms on which the locking tongues are supported in connection with the body and key controlled member of the lock in such a manner that the initial unlocking 20 movement of the arms takes place inwardly and laterally of the pipe and lock barrel; or in such a direction that the tongues are released from contact with the wall of the tube before any downward movement of the 25 tongues takes place.

In this manner the instant release of the tongues is had irrespective of any roughness or irregular surface of the tube, and a minimum of strain in the releasing movement is 30 placed on the key and the somewhat delicate lock mechanism.

A further object of the invention is to produce a simple and inexpensive device and yet one which will be exceedingly effective 35 for the purpose for which it is designed.

These objects I accomplish by means of such structure and relative arrangement of parts as will fully appear by a perusal of the following specification and claims.

40 In the drawing similar characters of reference indicate corresponding parts in the several views:

Fig. 1 is a sectional elevation of my improved lock and cap unit showing the lock engaged with an outlet tube or pipe.

Fig. 2 is a similar view showing the locking tongues as initially retracted by the turning of the key.

50 Fig. 3 is a sectional plan on the line 3—3 of Fig. 1.

Fig. 4 is a fragmentary side view, partly in section, on the line 4—4 of Fig. 1.

Referring now more particularly to the characters of reference on the drawing, the numeral 1 denotes a cylindrical body or barrel which is adapted to have a free fit in an inlet pipe or filler tube 2 and is provided with an enlarged head 3 on its upper end. The head overhangs the top of the pipe and is provided with a countersunk gasket ring 4 adapted to engage the top edge of the pipe to form an air-tight seal therewith.

The body is provided with a central bore 5 which extends from the bottom nearly to the top of the head; diametrically opposed slots 6 being cut through the body from the bore to the sides of the same and extending from the bottom of the body to a point short of the gasket 4.

Disposed in the body in crossing relation to each other are arms 7 which project into the slots and across the bore. These arms are separately pivoted toward their outer upper ends on eccentrics 8. On their outer ends the arms are fitted with transversely extending sharp edged locking tongues 9 which are of relatively hard metal and are curved along their outer edges to follow the contour of the pipe 2.

Extending lengthwise in the bore 5 is a link 10 which projects between the arms 7. A pin 11 flexibly connects the arms and link, said pin working in longitudinal slots 12 in the arms and a similar slot 13 in the link. A compression spring 14 in the slot 13 below the pin 11 exerts an upward pressure against the latter and acts to turn the lower ends of the arms 7 upwardly and thus extend the tongues outwardly of the body. The upper end of the link is connected to a crank 15 whose rotation is controlled by a key insertable in the barrel of a lock of the standard cylinder and pin type and which is countersunk in one side of the head 3 in the same manner as shown in said patent.

The eccentrics 8 are fixed on pins 16 which are turnably supported in the body; said eccentrics having arms 17 secured thereto to the sides of the arms 7 and overlapping the link on opposite sides of the same and above

the slot 13. The outer ends of the arms 17 are slotted as at 18, the slots being engaged by a cross pin 19 fixed in the link.

In the normal position of the parts or when 5 they are in locking relation with the pipe, the crank 15 is at its upper dead center position, as shown in Fig. 1. The link and the arms 17 are then in their uppermost position while the lower portions of the arms 7 are 10 near their uppermost position. The slot 13 then extends some distance above the pin 11, as shown in Fig. 1, the upward movement of the pin and arms 7 being limited by stops 20 projecting inwardly from the walls of the 15 slots 6 and overhanging the lower portions of said arms, so that the springs 14 cannot force the pin 11 to the top of the slot 13. The locking tongues then engage the walls of the tube or pipe and any pulling up on the cap 20 only tends to move the tongues outwardly and into firmer engagement with the pipe as fully shown and described in said patent.

When the crank 15 is lowered by the turning of the key in the lock the link 10 is lowered also. In the previous device this lowering of the link was immediately accompanied by a depression of the lower portion of the arms 7 which imparted an upward movement to their upper ends and to the tongues. This 30 feature as stated in the preamble of this application sometimes caused the tongues to catch against the tube if the same was rough and interfered with the easy release of the tongues, besides placing an excessive strain 35 on the delicate mechanism of the lock itself. In the present invention this is avoided by the use of the eccentrics on which the arms are turnably mounted and by the manner in which the eccentrics are connected to the link.

40 When the crank is in its topmost position as above stated the eccentrics are so positioned relative to their pivot pins 16 that with the initial lowering of the link and turning of the eccentric arms, the corresponding rotation of the eccentrics pulls the tongue arms inwardly. With this initial inward movement of the arms there is no lowering movement of the same, since such lowering movement is controlled by the engagement of the 45 upper end of the slot 13 with the pin 11; and as previously stated said upper end is normally some distance above the pin. The link must therefore be lowered some distance before the engagement of the slot with the pin 50 takes place and this distance is proportioned so that a sufficient turning movement of the eccentrics to draw the arms inwardly is had.

It is here to be noted that while I have shown this movement of the arms in the drawing as being considerable, this showing is somewhat exaggerated and for the purposes of clearness of illustration only; since in practice a very slight movement is sufficient to effect the desired disengagement of the 60 tongues from the pipe.

A passage 21, extending from top to bottom, is drilled through the body and head to one side of the bore 5 and on the opposite side of the head from the lock barrel. This passage is normally closed by a removable plug 76 22 of suitable character, and is for the purpose of inserting a gauge rod or other device, to ascertain the depth of the liquid in the tank or drum if desired without removing the cap. 75

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims. 80

Having thus described my invention what I claim as new and useful and desire to secure by Letters Patent is: 85

1. In a cap and lock structure for tubular outlets which includes a body to depend into and form a self-supporting cover over the outlet, arms having tongues on their outer ends to engage the inner wall of the outlet, means pivoting said arms intermediate their ends in the body, the arms having a downward slant from their upper ends, and means to move the lower ends of the arms downwardly whereby they will turn on their pivots and their upper ends will move inwardly and upwardly; means included in part with the pivot mounting means and with the arm 95 moving means to cause the upper ends of the arms to be retracted in a direct inward direction before any raising of the same takes place. 100

2. In a cap and lock structure for tubular outlets which includes a body to depend into and form a self-supporting cover over the outlet, arms having tongues on their outer ends to engage the inner wall of the outlet, means pivoting said arms intermediate their ends in the body, the arms having a downward slant from their upper ends, means to move the lower ends of the arms downwardly whereby they will turn on their pivots and their upper ends will move inwardly and upwardly, and means functioning with the initial movement of the arm moving means to retract the upper ends of the arms in a direct inward direction before any raising of the same takes place. 110 115

3. In a cap and lock structure for tubular outlets which includes a body to depend into and form a self-supporting cover over the outlet, arms having tongues on their outer ends to engage the inner wall of the outlet, the arms having a downward slant from their upper ends; eccentrics forming pivot members for the arms intermediate their ends, pins turnably mounting the eccentrics in the body, means applied to the arms to move the 120 125 130

lower ends of the same down, and means between said arm moving means and the eccentrics to rotate the latter an amount sufficient to withdraw the tongues from engagement with the outlet before any downward movement of the arms takes place.

4. In a cap and lock structure for tubular outlets which includes a body to depend into and form a self-supporting cover over the outlet, arms having tongues on their outer ends to engage the inner wall of the outlet, the arms having a downward slant from their upper ends; eccentrics forming pivot members for the arms intermediate their ends, pins turnably mounting the eccentrics in the body, a pin flexibly connecting the arms toward their lower ends, a link extending lengthwise in the body and having a slot through which the last named pin projects,

means to move the link downwardly from a predetermined position, the slot being arranged relative to the pin so that the top wall of the slot engages the pin only after a certain downward movement of the link has taken place, and means to turn the eccentrics with such certain downward movement of the link in a direction to cause the upper ends of the arms to be moved laterally and inwardly.

5. A structure as in claim 4, in which said last named means comprises arms rigid with the eccentrics and projecting thence in overlapping relation to the link, and a cross pin mounted on the link and engaging said eccentric arms.

In testimony whereof I affix my signature.

WILLIAM P. LOWTHER.
